UNITED STATES PATENT OFFICE.

HENRY STOCKMAN, OF PHILADELPHIA, PENNSYLVANIA.

LAST-SUPPORTING JACK.

SPECIFICATION forming part of Letters Patent No. 340,062, dated April 13, 1886.

Application filed September 29, 1885. Serial No. 178,571. (No model.)

To all whom it may concern:

Be it known that I, HENRY STOCKMAN, a citizen of the United States, residing at Philadelphia, in the county of Philadelphia and State of Pennsylvania, have invented certain new and useful Improvements in Last-Supporting Jacks, of which the following is a specification, reference being had therein to the accompanying drawings.

10 This invention relates to jacks for supporting shoe-makers' lasts; and the novelty consists in the construction, arrangement, and adaptation of parts, as will be more fully hereinafter set forth, and specifically pointed out 15 in the claims.

The object of the invention may be briefly stated to be the provision of various adjustabilities and interchangeabilities in the parts, whereby, first, the article upon the last may 20 be readily thrown into various positions for convenience to the operator; and, second, the jack, by certain simple changes, may be quickly adapted to either a reversible iron last or a wooden last at will.

25 I provide, in connection, a base which is secured to the table or bench, a hinged sub-base which supports the last-holding jack, and means for conveniently adjusting and locking said sub-base at any desired point, and the 30 sub-base turning on its hinge-pivot. In addition to this adjustment, I provide that the jack-body shall be loosely secured to this sub-base, so as to turn freely upon a central pivot, the latter plane of motion being at right angles to 35 that of the sub-base, whatever be the relation of said sub-base to the horizontal plane of the stationary base. I secure the jack-body at any desired point of adjustment by novel and important means, which allow the necessary 40 changes to be made easily and instantly. The jack, thus turning on two centers, is adapted to serve with a reversible last of the class set forth in my application Serial No. 173,240; but in the present invention I provide additional devices, which, used in connection with 45 the jack-body, convert the same into a device for holding a wooden last. These additional devices are readily removable and materially modify the capacity of the jack.

The invention is illustrated in the accompanying drawings, which form a part of this specification, and in which—

Figure 1 is a side elevation of a jack embodying my improvements and provided with a reversible metal last. Fig. 2 is a top plan view of the jack, the last removed therefrom. Fig. 3 is a vertical longitudinal section on the line xx of Fig. 2. Fig. 4 is a top plan view of the upper sub-base supporting the jack-body. Fig. 5 is a similar view of the base to which said sub-base is attached. Fig. 6 is a transverse sectional view taken on the line yy through the base, sub-base, and lower part of jack-body. Fig. 7 is a modified form of the means for securing the reversible last to the jack. Fig. 8 is an elevation of one side of my improved jack, showing attachments for holding a wooden last. Fig. 9 is a similar elevation of the opposite side. Fig. 10 is a vertical longitudinal section on line zz of Fig. 11. Fig. 11 is a plan view showing wooden last removed. Fig. 12 is a transverse section on line 11 of Fig. 11. Fig. 13 is a detail sectional view on line 22 of Fig. 9. Figs. 14 and 15 are detail views of the means employed to secure the jack-body to the base.

Referring to the drawings, A designates the stationary base, having means, a , by which it is secured to any convenient table or bench, and to this base A is hinged at b the sub-base B. In the center of the base A is a slot, a' , in which is received a curved bar, C, made in the form of a segment upon the arc of a circle having the pivot of the hinge b for a center. Guides a'' receive a locking pin or screw, C', which serves to lock the bar C at any desired point of adjustment, and the bar C has a rectangular head, c , which fits into a recess, b' , formed in the under face of the sub-base B, a threaded shank, c' , passing up through said sub-base, and serving to lock the jack-body D thereto, as will presently appear.

The base A and sub-base B are so adapted to each other as to fold closely together—that is to say, the guides a'' of the part A are received within recesses in the sub-base B, and the locking-bar C, which moves with the sub-base, passes through the slot a' of the base A,

and through its supporting-bench. The pin or set-screw C also operates in a recess formed partly in each of the parts A B.

Upon the upper face of the sub-base B is a 5 circular guide, b^2 , having the aperture b^3 , which receives the threaded arm c' of the locking or adjusting bar C for a center. This guide b^2 is received in a circular recess, d, formed in the lower face of the base D' of the 10 jack-body D, and this recess d has for its center an aperture, d' , in said base, which also receives the threaded arm c' of the adjusting-bar C. The upper face of the base D' is provided with a double cam, d^2 , which corresponds 15 with a similar cam-face, f, formed on a lever-nut, F, as shown.

The arm c' of the adjusting-bar C works loosely through both apertures b^3 and d' ; but the parts D' and B may be closely clamped together by means of the frictional engagement 20 of the cam-faces d^2 and f, which may be accomplished by simply throwing the handle of the lever-nut F in the proper direction.

The movable jack-body D comprises the 25 base D', the toe-standard D², having transverse rib x', the pin x², and the standard d², having the aperture x. These parts are shown in the application hereinbefore mentioned; but in the present invention the parts have 30 additional and important functions, as will be seen. The pin x² is received in the socket g of the reversible last G, while the aperture x receives the clamp g'. I may in this invention dispense with the clamp g' and use a 35 screw, as seen at g², and still have an important function for the aperture x.

As thus far described, it will be observed that the base B may be adjusted in one direction back and forth and locked in desirable 40 location at will, and the jack has independent adjustment in another plane and means for locking it at any desired point at will, the base turning upon the pivot b, and the jack turning in a direction at right angles thereto 45 upon the arm c'. The last, being held upon the standards D² D³, as described, may by these independent adjustments be thrown into various positions to operate upon the work.

This device is useful and supplies a want; 50 but I enlarge the scope of its usefulness by the devices which I will now describe.

Within the aperture x (the clamp g' having been removed) of the standard D², I journal a lever, H, having a squared portion, h, which 55 is received in a similar aperture, i, formed in a swinging stud, I, having a pin, i', which fits into and holds a wooden or other last, J. The lever-arm of the part H has a slot, h', which receives a threaded bolt, K, and a thumb-nut, k, serves to depress the lever. These 60 parts are so proportioned and arranged relatively to each other that when the thumb nut k is loosened the last J may be readily placed upon the pin i', and when the said nut is

screwed down to depress the lever the toe of 65 the last will be thrown upon any suitable support to lock the last firmly in place.

L designates a removable frame or casting 70 having a sleeve, l, which receives the standard D², and a slot, l', in said sleeve, which receives the rib x', to prevent the casting L from turning. Upon the parallel sides of the body of this casting I engage the jaws M of a toe-rest, M', and by a pinching-screw, m', I adjust this toe-rest upon the casting to accommodate different lengths of last. Now, it will be observed that, a last having been engaged upon the pin i' and the lever H depressed by screwing down the nut k, the toe of the last will be held forcibly upon the toe-rest M', 80 and by means heretofore described the said last may be held firmly in various positions to accommodate the workman. It will further be observed that while the jack D may be readily made to serve with a last, G or J, 85 the standards D² and D³ have interchangeable functions, while the aperture x and ribs x' have functions which modify either set of interchangeable devices.

The rib x' strengthens the standard D' when 90 a last, as G, is in use, and the same rib serves to prevent the frame L from turning when a last, as J, is being held. The aperture x also may either hold the clamp g', or it may be the journal-bearing of the lever H. The 95 several parts are removable and readily interchangeable, while the adjustments mentioned as belonging to the jack are equally applicable to either form given to the device in use.

In details of construction modifications may be made within wide limits without departing from the principle or sacrificing the advantages of my invention, the essential features of which have been given.

The subject-matter of claim 4 herein is shown but not claimed in another application filed by me November 25, 1885, No. 183,956.

What I claim as new is—

1. The combination, with an adjustable base and a jack pivoted to said base, and means, substantially as described, for locking said base at any desired point of adjustment, of lever F, fitting over the upper end of the locking-bar C, substantially as and for 115 the purpose set forth.
2. The combination, with the base A, having guides a² and slot a', of the hinged sub-base B, having central aperture, b³, and guide b², the segmental bar C, pin C', and last-supporting jack, as set forth.
3. The combination, with the hinged base B and jack D, having rotary movement thereon, and a cam-face, as d, of an adjusting-bar, as C', and a lever-nut, as F, having corresponding cams, f, as set forth.
4. In a last-jack, as described, the combination, with a lever, as H, and a last-holding

device having last-pin, as *i*, of a threaded bolt and thumb-nut for moving and holding the lever, as set forth.

5. The combination, with the jack D, having independent adjustments on planes at right angles to each other, of removable interchangeable devices, as L, M, H, and I, and locking-screws, as *k m'*, as set forth.

6. The combination, with the jack D, hav-

ing standards D² D³ and rib *x'*, of the frame to toe-rest M, lever H, holder I, and set-screws, as and for the purpose set forth.

In testimony whereof I affix my signature in presence of two witnesses.

HENRY STOCKMAN.
